JOSEPH H. VINEBERG, JOHN HALLIDAY, AND JOSEPH PRESNER, OF MONTREAL, QUEBEC, CANADA, ASSIGNEES TO THE V. P. AUTO APPLIANCE COMPANY, LIMITED, OF MONTREAL, CANADA.

WINDSHIELD ATTACHMENT.

1,426,793.

Specification of Letters Patent. Patented Aug. 22, 1922.

Application filed July 14, 1921. Serial No. 484,743.

To all whom it may concern:

Be it known that we, JOSEPH H. VINEBERG, JOHN HALLIDAY, and JOSEPH PRESNER, all subjects of the King of Great Britain, and 5 residents of the city of Montreal, Province of Quebec, Dominion of Canada, have invented certain new and useful Improvements in Windshield Attachments; and we do hereby declare that the following is a 10 full, clear, and exact description thereof.

Our invention relates particularly to attachments of the type disclosed in a pending application Serial No. 443,466 for shielding the eyes of the occupants of motor vehicles from the sun's rays and for protecting 15 the wind shield glass particularly the upper section of the latter from rain, snow or sleet.

The object of the present invention is to 20 provide an attachment of this nature possessing increased efficiency and greater durability and which can be manufactured at a comparatively low cost.

To this end our invention consists of the 25 construction, combination and particular arrangement of the parts hereinafter described and illustrated and pointed out in the claims.

Figure 1 is a plan view of the underside 30 of a wind shield attachment constructed according to our invention;

Figure 2 is a longitudinal sectional view of the tubular casing containing the spring roller upon which the blind is wound;

Figure 3 is a fragmentary view partly in 35 longitudinal section illustrating the manner of mounting the blind upon the roller;

Figure 4 is a sectional view taken on line 4—4 Figure 1;

Figures 5, 6 and 7 are detail views of one 40 of the blind projecting arms;

Figures 8 and 9 are detail sectional views of the roller and casing taken on lines 8—8 and 9—9 respectively Figure 3;

Figure 10 is a sectional view taken on line 45 10—10 Figure 11;

Figures 11 and 12 are detail views of the locking means for retaining the blind in its withdrawn position;

Figure 13 is a sectional view taken on line 50 13—13 Figure 2; and

Figure 14 is a detail view of the brackets for mounting the attachment upon a wind shield.

The accompanying drawing illustrates the preferred embodiment of our invention 55 which consists of a tubular casing 2 having a longitudinal opening 3 and closed ends 4 and 5. This casing contains an all-metal roller 6 which is journaled in the ends 4 and 5 respectively, the roller having wound thereon a blind 7 which is adapted to be extended outwardly through the opening in the casing. Means for extending the blind comprises a pair of lever arms 8 and 9 one of which is pivotally mounted upon each end 65 of the casing 2 with the front ends of the arms in operative engagement with a reinforcement device 10 upon the front edge of the blind and adapted to swing outwardly from a position substantially parallel to the 70 casing to a position oblique thereto the latter position being determined by the size of the blind.

This reinforcement device preferably consists of a sheet-metal member bent to substantially U-form in cross-section to present a channel 12 into which the said front end of each lever arm projects. The latter is of angular cross-section between its ends and is so disposed that one flange is adapted to 75 operate within the channel 12 such flange lying within the channel substantially throughout its length when the blind is in the withdrawn position. The outer end of such flange is of increased width and presents a curved bearing surface 13 the curve 80 being sufficiently wide to prevent undue wear on the reinforcement member 10. The opposite end of each arm is forked as at 14 to effect its pivotal connection to the adjacent 85 end of the casing and it is provided with a tail 15 which is operatively connected to the corresponding tail on the other arm by springs 16 and 17 the springs imparting to the arms a tendency to swing outwardly relatively to the casing for the purpose of yieldingly maintaining the blind in extended position. This construction and arrangement 90 of parts also maintain the front ends of the arms in bearing relation with the reinforcement member 10 without the aid of means for fastening the reinforcement member and arms together thereby providing a more durable, cheaper and more efficient construction than is obtainable if additional means 95 for securing each arm to the reinforcement

100

105

bar were employed. Furthermore such construction permits of easy assembly and does not require the same care and accuracy in the manufacture as is required if such additional means were used.

In order to provide a light but durable roller the latter is constructed of a tubular member 18 the ends of which are closed by sheet-metal discs 19 and 20 of a diameter 10 to be fitted within the ends of the tube and provided with preferably three lugs or clips 21 which are sprung over the adjacent end of the tube, the clips being of sufficient depth to present a shallow socket 22 at each 15 end of the roller into which a hub or boss 23 projects, this boss being formed integral- 20 ly with each of the casing ends 4 and 5 respectively. The closure 19 rigidly carries a trunnion 24 which is journaled in the 25 adjacent boss. The mount for the roller at its opposite end is effected by a comparatively short shaft 25 disposed longitudinally within the roller tube and having its inner end rotatably mounted in a block 26 rigidly secured within the tube. The outer end 30 of the shaft projects through a central opening 27 in the disc 20 and is flattened as at 28 and inserted into a slot in the adjacent boss on the casing end, the shaft being thus held against rotation but permitting rotation 35 of the roller. A connection between the two is effected through a helical spring 29 which encircles the shaft throughout its length and has its inner end secured in a slot or opening 30 in such shaft its opposite end 31 projecting through a hole 32 in the disc 20.

As hereinbefore stated, the size of the blind determines the extent of its projection, 40 that is to say, it is extended until completely unwound from the roller. It is obvious, therefore, that the connection of the inner end of the blind to the roller must be such that such inner end will not be subjected 45 to undue wear and tear when the fluid is extended. To provide such a connection which will also enable the blind to be readily detached from the roller the tube 6 is provided with a longitudinal opening 33 extending throughout its length and the edges thereof are bent back as at 34 and 35 for reinforcement purposes. The blind is adapted to be projected through this opening and its inner end is sewn around a rod 50 36 located within the roller and extending throughout the length of the same and of a diameter larger than the width of the opening for preventing complete displacement from the roller. Each end of the rod is 55 provided with an eye 36^a and the blind is stretched thereon and secured thereto at its ends by wire fastenings which are threaded through such eyes thereby preventing wrinkling in service. In order to ensure 60 uniform winding of the blind on the roller 65

and to relieve the inner end of the blind of undue wear when in such position the curve of the portion of the tube terminating in the edge 35 is described on a larger radius than that portion terminating in the edge 34. 70 This also provides means for preventing rotation of the disc 20 relatively to the tube 6 as the former is provided with a notch 40 in its periphery which is adapted to be engaged by the adjacent edge 34 the latter 75 acting as a pawl preventing such rotation. This may be employed at opposite ends of the roller if it is desired to have a closure for such end detachable, one end however only need be detachable to permit insertion 80 of the rod 36 into the roller. It may be found desirable to employ blocks similar to the block 26 spaced throughout the length of the tube 6 for the purpose of reinforcement. The block 26 is cut away as at 41 to accommodate the rod 36. The outer end of the blind is secured to the reinforcement bar 10 the connection being effected by carrying the blind over the front edge of the bar and beneath the same where it is secured in a 90 relatively small tube 43 formed by bending the adjacent edge of the bar to cylindrical form, the blind being secured in the tube by a rod 44 which is sewn into the blind and its ends being secured to the ends of the 95 blind in a similar manner to rod 36. The rod is adapted to be inserted into the tube endwise the longitudinal opening 45 being provided to accommodate the blind.

In order to withdraw the blind a wire- 100 cord 46 is secured to the underside of the bar 10 is passed through a lock 47 mounted on the casing 2 to a point in the vehicle within reach of the driver whereby the latter by a pull on the cord may withdraw the 105 blind when desired. The lock 47 which maintains the blind in the withdrawn position consists of a unitary member 48 having a tapered opening 49 through which the cord passes. Positioned centrally of the 110 mouth of the larger end of such opening is a movable jaw 50 actuated by a spring 51. This jaw has concave faces 52 and 53 and is adapted to engage an enlargement 54 on the cord. The cord may be released from the 115 position in which it is locked by the jaw by moving the cord with its enlargement laterally until such enlargement clears the jaws.

The springs 16 and 17 are of sufficient strength to overcome the spring 29 so that 120 the blind, unless held in withdrawn position by the cord 46, will normally assume its extended position. The casing 2 is adapted to be secured to the motor vehicle in any preferred manner. In the accompanying 125 drawing a forked bracket 55 is mounted upon each end of the casing 2 and adjustably carries a pair of clamping jaws 56, the adjustment enabling the attachment to be secured to windshields of varying width. 130

This adjustment is obtained by slidably mounting the head of a bolt 57 which carries the jaws in the fork of the bracket.

What we claim is as follows:

5. 1. A storm and sun shield comprising a roller, a blind wound upon the roller, a device secured to the front edge of the blind and presenting an open channel, and means for extending said blind, said means projecting into the channel in said device and in sliding relation with the latter.
10. 2. A storm and sun shield comprising a roller, a blind wound upon the roller, a reinforcement member secured to the front edge of the blind and presenting a longitudinal open channel, lever arms pivoted at points adjacent the opposite ends of the roller and having their front ends projecting into said channel and in sliding relation with the said member and means for yieldingly maintaining the arms in position with the blind extended.
15. 3. A storm and sun shield comprising a roller; a blind wound upon the roller, a reinforcement member secured to the front edge of the blind and presenting a longitudinal channel, lever arms pivoted at points adjacent opposite ends of the roller and having their front ends projecting into said channel and in bearing relation with said member and springs adapted to yieldingly maintain the arms in positions with the blind extended.
20. 4. A storm and sun shield comprising a roller, a blind wound upon the roller, a reinforcement member secured to the front edge of the blind and presenting a longitudinal channel, lever arms pivoted at points adjacent opposite ends of the roller and having their front ends in bearing relation with said member for the purpose of extending the blind, the said arms being of angular cross-section and so disposed that one flange of each is adapted to operate within said channel, and means yieldingly maintaining the arms in positions with the blind extended.
25. 5. A storm and sun shield comprising a roller, a blind wound upon the roller, a reinforcement member secured to the front edge of the blind and presenting a longitudinal channel, lever arms pivoted at points adjacent opposite ends of the roller and having their front ends in bearing relation with said member for the purpose of extending the blind, said front ends being enlarged and presenting curved bearing surfaces, and means for yieldingly maintaining the arms in positions with the blind extended.
30. 6. A storm and sun shield comprising a tubular casing, an all metal roller journaled therein and comprising a tubular member having a longitudinal opening and having open ends, a closure for one of said ends, a trunnion carried by said closure and jour-
- nalled in the adjacent end of said casing, a bearing rigidly mounted within said member a short distance from its opposite end, a detachable closure for such end, said closure having a central opening, a shaft located 70 within said member with its inner end journaled in said bearing and having its outer end projecting through the opening in said closure and fixed against rotation in the adjacent end of the casing, a helical spring encircling said shaft and having one end connected thereto and having its opposite end connected to the detachable closure, a blind wound upon said roller and having its inner end extending through said opening in the 75 roller, a rod located within the roller and secured to said inner end of the blind for the purpose of preventing complete displacement of the latter from the roller, a reinforcement device secured to the outer end 80 of the blind, said device having a channel, means for extending the blind outwardly through the opening in the casing said means extending into the channel in said member and in bearing relation with the 85 latter, and means for withdrawing the blind.
7. A storm and sun shield comprising a roller, a blind wound upon the roller; means for extending the blind and means for withdrawing the blind from extended position 90 and for locking the same in the withdrawn position, said last mentioned means consisting of a device located in fixed position and having a slot therein, a cord secured to the front end of the blind and passed 95 through said slot, said cord carrying an enlargement adjacent one end and a locking member mounted in said device and movable transversely to the cord and adapted to engage said enlargement for the purpose of 100 maintaining the blind in the withdrawn position.
8. A storm and sun shield comprising a roller, a blind wound upon the roller; means for extending the blind and means for withdrawing the blind from extended position 105 and for locking the same in the withdrawn position, said last mentioned means consisting of a device located in fixed position and having a slot therein, a cord secured to the front end of the blind and passed 110 through said slot, said cord carrying an enlargement adjacent one end and a locking member mounted in said device and movable transversely to the cord and adapted to engage said enlargement for the purpose of 115 maintaining the blind in the withdrawn position, said slot presenting openings on opposite sides of the locking member adapted to permit passage of the said enlargement 120 for the purpose of permitting the release of the blind from the withdrawn position.
9. A storm and sun shield comprising a roller, a blind wound upon the roller and a bar reinforcing the front end of the blind 125

and consisting of an open channel having one of its flanges terminating in a tube, said blind being carried over the top flange and extending beneath said bottom flange and secured within said tube; means for projecting said blind consisting of arms hinged adjacent the roller and having their free ends extending beneath the blind into said channel and in sliding relation with the latter.

In testimony whereof we have signed our names to this specification in the presence of two witnesses.
